UNITED STATES PATENT OFFICE.

ELIJAH O. ROGERS, OF ADA, OKLAHOMA.

DRENCHING-BOTTLE.

1,274,454.

Specification of Letters Patent. Patented Aug. 6, 1918.

Application filed January 26, 1914, Serial No. 814,491. Renewed November 18, 1917. Serial No. 201,875.

To all whom it may concern:

Be it known that I, ELIJAH O. ROGERS, a citizen of the United States, residing at 513 East 10 street, Ada, in the county of Pontotoc, State of Oklahoma, have invented certain new and useful Improvements in Drenching-Bottles; and I do hereby declare the following to be a full, clear, and exact description of the invention, such as will 5 enable others skilled in the art to which it appertains to make and use the same.

This invention relates to drenching bottles for administering medicine to animals.

The object of the invention resides in the 15 provision of a drenching bottle which embodies improved means for controlling the delivery of liquid from the interior thereof.

A further object of the invention resides in the provision of a drenching bottle which 20 can be utilized with facility to effect either a gravity feed of liquid or a force feed thereof into the mouth of an animal.

A still further object of the invention resides in the provision of a drenching bottle 25 which will be simple in construction, efficient in use and which may be manufactured at a comparatively small cost.

With the above and other objects in view the invention consists in the details of construction and in the arrangement and combination of parts to be hereinafter more 30 fully described and particularly pointed out in the appended claim.

In describing the invention in detail reference will be had to the accompanying 35 drawings wherein like characters of reference denote corresponding parts in the several views, and in which—

Figure 1 is a vertical section of the improved 40 drenching bottle in position to be filled with medicine;

Fig. 2, a view similar to Fig. 1 with the bottle in delivery position and the valve controlling the delivery of medicine therefrom 45 in closed position;

Fig. 3, a detail perspective view of the operating lever of the bottle;

Fig. 4, a vertical section of the bottle 50 showing a syringe structure associated therewith and a discharge nozzle attached to the delivery end of the bottle;

Fig. 5, a perspective view of the piston element and the cap supporting same, and

Fig. 6, a perspective view of a spraying 55 nozzle adapted to be used when the syringe structure is employed.

Referring to the drawings the improved drenching bottle is shown as comprising a tubular body 10 one end of which is reduced to form a discharge spout 11 which is 60 threaded exteriorly at its outer end as at 12. The outer end of the major portion of the body 10 is also threaded exteriorly as at 13. Threaded on the outer end of the major portion of the body 10 is a cap 14 having a central dished portion 15. Projecting from the base of the dished portion is a tubular extension 16 in which is slidably mounted a rod 17. This rod 17 extends through the base of the dished portion 15 and the end 70 thereof adjacent the cap 14 is slidably engaged in a bridge 18 carried by the cap and extending across the base of the dished portion. The end of the rod 17 remote from the cap 14 carries a valve 19 which seats in the 75 inner end of the spout 11 and serves to prevent the flow of liquid from the interior of the body 10 through the spout 11. The valve 19 is normally held seated in the inner end of the spout 11 by means of a spring 20 80 which encircles the rod 17 and has one end bearing against the bridge 18 and its other end against a flange 21 formed on said rod. The valve 19 is adapted to be moved from its seat in the spout 11 to permit the passage 85 of liquid from the interior of the bottle through the spout by means of an angle lever 22 pivoted on the cap 14 and having one end thereof forked and disposed in embracing relation to the rod 17 just inwardly 90 of the flange 21. The end of the lever 22 remote from the rod 17 terminates in a handle 24 whereby said lever may be conveniently rocked with the hand to move the valve 19 from closed position as will be 95 obvious.

If it is desired to use the bottle in the nature of a syringe the cap 14 has slidably mounted therein a piston rod 25 which carries a piston 26 slideable in the major portion 100 of the body 10. The outer end of the piston rod 25 terminates in a handle 27 whereby said rod may be readily reciprocated. When using the bottle as a syringe if it is desired to discharge the liquid in a fine stream a nozzle 28 is threaded on the outer end of the spout 11. If it is desired to discharge the liquid in the form of a spray a spraying nozzle 30 is threaded on the outer end of the spout 11. 105

What is claimed is:—

A drenching bottle comprising a tubular

body having one end reduced to form a discharge spout, a cap threaded on the other end of said body and forming the bottom of the bottle, said cap having its central portion depressed and extending into the body, 5 a hollow cylindrical shield carried by the depressed portion of the cap and extending longitudinally of the bottle within the latter, a rod slidable in the bottom of said depressed portion and in one end of the shield, a valve carried by the inner end of the rod and adapted to seat in the inner end of the spout, a bridge embodied in said cap exteriorly of the bottle and in which the rod 10

also slides, a flange on the rod between the bridge and the outer face of the bottom of the depressed portion of the cap, a spring encircling the rod and bearing against the bridge and flange to normally hold the valve seated, and lever operated means mounted on the cap for moving the valve from its seat.

In testimony whereof, I affix my signature, in the presence of two witnesses.

ELIJAH O. ROGERS.
